CLAIM

The ornamental design for an ice ball maker, as shown and described.

DESCRIPTION

FIG. 1 is a front perspective view of an ice ball maker, showing my new design;

FIG. 2 is a front elevational view thereof, the rear elevational view is identical;

FIG. 3 is a left elevational view thereof, the right side view is identical; and,

FIG. 4 is a top side view thereof.

(Continued)

The broken lines in the figures are for the purposes of illustrating portions of the ice ball maker, which form no part of the claimed design.
